UNITED STATES PATENT OFFICE.

FRANK McGORVIN, OF REDDING, CALIFORNIA.

CORRUGATED-IRON SHEARS.

1,112,076.

Specification of Letters Patent. Patented Sept. 29, 1914.

Application filed November 24, 1913. Serial No. 802,612.

To all whom it may concern:

Be it known that I, FRANK McGORVIN, a citizen of the United States, residing at Redding, in the county of Shasta and State of California, have invented new and useful Improvements in Corrugated-Iron Shears, of which the following is a specification.

This invention relates to shears which are particularly adapted for cutting corrugated iron.

10 The object of the invention is to provide a simple and substantial and easily operated pair of shears, which shears are constructed with the object in view of preventing the corrugated iron from becoming flattened while being cut, and which will also prevent any slipping of the iron with relation to the knife and cutting edge.

Further objects will hereinafter appear.
20 The invention consists of the parts and the construction and combination of parts as hereinafter more fully described and claimed, having reference to the accompanying drawings, in which—

25 Figure 1 is a plan view of the shears showing a portion of the knife broken away. Fig. 2 is a side elevation of the shears. Fig. 3 is a cross section on X—X, Fig. 2. Fig. 4 is a perspective view of the removable spacing plate.

Referring to the drawings, A and B indicate a pair of plates between which is pivotally mounted, as at 2, a knife or cutter C. The opposite ends of the plates are held 35 apart by a spacing plate 3 and secured together by a bolt 4. One of the plates, as A, is in this instance provided with a pair of raised portions 5 and a corresponding intermediate depression 6, said raised portions 40 and recess being of a contour which will conform with the corrugations usually formed in corrugated iron. The plate A is also provided for the purpose of forming a shearing edge for the knife C.

45 In operation when it is desired to cut a plate of corrugated iron crosswise of the corrugations, it is accomplished by slipping the plates A and B under the iron until the raised portions and recess 6 register with 50 the lower contour of same. The knife C is then depressed by the handle 7 and is thus caused to cut the plate on the line of the corrugated cutting edge formed on the plate A. The corrugated edge thus formed on the plate 55 prevents the corrugated iron from flattening out while being cut and, further

more, prevents any slipping of the plate with relation to the knife and cutting edge.

By referring to Fig. 1 it will be seen that the knife is made slightly tapering, being 60 narrow at the pivot point and broadest near the handle. This peculiar shape is provided for the purpose of spreading the severed portion of the iron so as to prevent any binding action when the knife is returned. 65 The pivot member 2 constructed as here shown not only serves the purpose of a pivot for the knife, but also acts as a clamp to secure the forward ends of the plates A and B. The spacing plate 3 may be changed 70 with thicker or thinner plates, when desired, for the purpose of widening or lessening the space between the plates.

A device constructed as here shown is simple and compact in construction and is 75 particularly suitable for cutting corrugated iron. I wish it understood, however, that the knife C may be provided with two cutting edges 8 and 9, the edge 8 being used in conjunction with the corrugated cutting 80 edge, while the cutting edge 9 may be used with the opposite side of the plates by inverting the apparatus, when it is desired to cut a straight plate. The lower face of plate B will then act as a cutting edge. The 85 shears are thus applicable for various purposes, such as cutting heavy straight plates or corrugated surfaces.

The materials and finish of the several parts of the shears are such as experience 90 and judgment of the manufacturer may dictate.

I wish it understood that various changes in form, proportions and minor details of construction may be resorted to within the 95 scope of the appended claims and that I do not wish to limit myself to the specific construction here shown.

Having thus described my invention, what I claim and desire to secure by Letters Patent is—

1. A shearing tool including a pair of spaced plates arranged in side by side relation one of which has a straight uninterrupted shearing edge and the other of which 105 has a corrugated-shaped shearing edge, and a knife pivotally mounted in the space between said plate and serving to hold the latter spaced at one end, said knife being received in the space between the plates and 110 having a shearing edge on each side thereof whereby one shearing edge of the knife co-

operates with the shearing edge of one plate and the opposite shearing edge of the knife coöperates with the shearing edge of the other plate.

- 5 2. A shearing tool including a pair of spaced plates arranged in side by side relation, said plates having upper and lower longitudinal shearing edges, and a blade also having upper and lower longitudinal
- 10 shearing edges pivoted between the plates, said plates and blade being invertible so as

to allow the shearing edges of the blade to coöperate with either the upper or lower respective shearing edges of the plates.

In testimony whereof I have hereunto set 15 my hand in the presence of two subscribing witnesses.

FRANK McGORVIN.
